UNITED STATES PATENT OFFICE.

THOMAS D. RICE, OF PAWTUCKET, RHODE ISLAND.

CUE-LOCK.

1,228,601.

Specification of Letters Patent. Patented June 5, 1917.

Application filed February 12, 1916. Serial No. 77,889.

To all whom it may concern:

Be it known that I, THOMAS D. RICE, a citizen of the United States, and resident of the city of Pawtucket, in the county of 5 Providence and State of Rhode Island, have invented certain new and useful Improvements in Cue-Locks, of which the following is a specification.

This invention relates to a cue lock such 10 as may be used for a billiard cue, pool cue or the like, so that the cue may be secured in position to prevent unauthorized persons obtaining access thereto. The object of my invention is the provision of a simple and inexpensive lock for a cue of the class described the same comprising a base portion containing locking mechanism and on which casing the end of the cue is adapted to rest whereby the locking mechanism is adapted 15 to be actuated by the operation of the cue, to cause the locking mechanism to engage and secure the cue to said base.

With these and other objects in view, the invention consists of certain novel features 20 of construction, as will be more fully described, and particularly pointed out in the appended claims.

In the accompanying drawings:

Figure 1—is a sectional elevation of the 25 base member and locking mechanism therein also showing the handle end of the cue in section in position on the lock base.

Fig. 2—is a top view of the locking member.

Fig. 3—is a section of the locking base member on line 3—3 of Fig. 1 showing the plan of the locking mechanism mounted therein.

Fig. 4—is a perspective view of the locking mechanism removed from the casing.

Fig. 5—is a view of the key for releasing the cue.

Fig. 6—is a view of the end of the cue.

Fig. 7—is a view illustrating the general 45 arrangement of a cue rack with the cue secured therein by my improved locking member.

Referring to the drawings 10 designates the lock base which is formed in an inverted 50 cup shape and is secured in position on the shelf or rack by means of a single screw 11 and a retaining pin 12 projecting outwardly from the lower edge of the base, which pin is adapted to be driven into the shelf to 55 prevent rotation of the base member when the screw is set into the same. A lock

frame 13 is shown in detail in Fig. 4, the same comprising an H-shaped casting having two center cross arms 14 bridging the space between the front and rear bars 15 and 16. These cross arms 14 are spaced apart providing room for a spring pin 17 which is provided with an end 18 extending into the bar and formed in a coil 19, and extending forward and then upward forming 65 the spring locking pin 17. This locking frame is held in position in the casing by a screw 20. When the frame is in position in the base member the spring pin 17 extends up through the hole 21 in the base and 70 above its surface. The two bars of the lock frame are provided with a plurality of holes 22 for the reception of the key controlling pin 23 which may be inserted into any one of these holes for the purpose of 75 changing the combination, thereby requiring a different key for each different lock.

Extending from the upper surface of this casing is a heavy spur or post 24 which has a barb or lip 25 extending laterally from its 80 side leaving a space 26 between it and the top of the base portion so that the plate on the cue end may pass thereunder for the purpose presently described.

The large end 27 of the cue 28 is counter-bored as at 29 and is provided with a plate 30, see Figs. 1 and 6, which is secured to the bottom of the cue by screws 31. This plate is provided with a round central opening 32 with a lateral opening 33 leading 90 therefrom for the reception of the barb 25 on the post 24. This plate is also provided with a small opening 34 for the reception of the end of spring pin 17.

In the operation of my improved locking device, I first secure the base portion of the locking member on the shelf portion of the rack by driving the pin 12 into the wood and then passing the large screw 11 down into the shelf or support thus the mechanism within the base is entirely inclosed and cannot be removed or tampered with when the cue is in position as at that time all of the fastening elements are covered.

In positioning the cue upon this base portion it is only necessary to pass it straight down so that the post 24 will pass through the opening 23 in its plate into the bottom of the cue and the barb 25 pass through the radial opening 33. This action presses the 105 spring pin 17 downward substantially flush with the face of the base portion, the cue is 110

now rotated bringing the barb around over the plate and the rotation continues until the hole 34 in the plate 30 registers with and permits the spring pin 17 to spring upward 5 into this hole thereby preventing further rotation of the cue in either direction, the barb now extends out over the plate 30 and effectually prevents the cue from being raised from the base portion.

10 It will be noted that when the cue is in this position all of the fastening screws both in the base portion and in the cue are covered and inaccessible.

15 The only way to release the cue is to pass the key 35 through the slot 37 in the base portion, this key is provided with edge slots 36 so arranged as to register with the pin 23 also with the cross bars 14 before it can be turned sufficiently to act upon and withdraw 20 the spring pin 17 sufficiently to permit the cue to be rotated back to its starting point whereby it may be readily raised from the base and released.

25 I have shown and described one illustrative embodiment of my invention but the same may be changed in many ways if desired, it is understood that although specific terms are employed they are used in a generic and descriptive sense and not for the 30 purpose of limitation, the scope of the invention being set forth in the following claims.

I claim:

1. A cue lock comprising a base portion 35 containing locking mechanism, a cue adapted to rest on said base, a post and a lock pin in the base, and means whereby the operation of the cue is adapted to cause said pin to operate to engage and secure the cue to 40 said base.

2. A cue lock comprising in combination a cue, a base portion on which the cue is adapted to rest and locking means in said base portion whereby the rotating of said cue on 45 said base operates the mechanism to lock the cue to said base.

3. A cue lock comprising a base having a post and containing locking mechanism, a cue having an opening in its base for the reception of said post and adapted to rest on 50 said base, and means whereby the operation of said cue causes said post to enter and engage said cue and secure said cue to said base.

55 4. A cue lock comprising a base having a barbed post and a spring pin also projecting

from its surface, a cue having a plate on its end adapted to receive said barbed post and also having a pin receiving opening, whereby when said cue is positioned and rotated 60 said spring pin enters its hole in said plate and prevents further rotation of the same, and a key for withdrawing said pin to permit the cue to be rotated back to release position.

5. A cue lock comprising an inverted cup-shaped base member in which the locking elements are housed, a central post having a laterally extending barb, and a spring actuated locking pin projecting from the upper face of the base, a cue having a central hole in its wall for receiving said post and barb, said cue also having a hole for the reception of said pin whereby when the cue is positioned and rotated on said base a predetermined distance the pin hole is caused to register with the pin which automatically enters the hole and prevents further rotation of the cue, and means for releasing the same.

6. A cue lock comprising an inverted cup-shaped base member in which the locking elements are housed, a central post having a laterally extending barb, a spring actuated locking pin projecting from the upper face of the base, a cue having a central hole in its 85 wall for receiving said post and barb when positioned thereon, said cue base also having a hole for the reception of said pin, whereby when the cue is positioned and rotated on said base a predetermined distance the pin 90 hole is caused to register with the pin which automatically enters the same and prevents further rotation of the cue, and a key for withdrawing said pin to permit said cue to be rotated back to the starting point to be 95 removed.

7. In a cue lock the combination with a cue, of a base portion containing the locking mechanism on which the end of the cue is adapted to rest, said locking mechanism being adapted to be operated by a movement of the cue to engage and lock the cue thereto, a key for releasing the locking mechanism and adjustable means in said mechanism to set said mechanism to different keys. 100 105

In testimony whereof I affix my signature in presence of two witnesses.

THOMAS D. RICE.
